UNITED STATES PATENT OFFICE.

CHARLES R. LONG, OF LOUISVILLE, KENTUCKY.

CHAIR-SEATING NEEDLE.

SPECIFICATION forming part of Letters Patent No. 278,982, dated June 5, 1883.

Application filed June 29, 1882. (No model.)

To all whom it may concern:

Be it known that I, CHARLES R. LONG, of Louisville, in the county of Jefferson and State of Kentucky, have invented a new and useful Improvement in Chair-Seating Needles, of which the following is a full, clear, and exact description.

Reference is to be had to the accompanying drawings, forming a part of this specification, in which similar letters of reference indicate corresponding parts in all the figures.

Figure 1 is a plan view of a portion of a chair-seat. Fig. 2 is a sectional elevation of a portion of my needle, showing part of a chair-frame. Fig. 3 is a side elevation of a portion thereof turned one-quarter of a revolution. Fig. 4 is a side elevation of the same turned through the second quarter of a revolution. Fig. 5 is a side elevation of the same turned 20 through the third quarter of a revolution. Fig. 6 is a sectional end elevation of the needle shown in the first position, and illustrating its use. Fig. 7 shows an elevation of the needle and a section of portions of a chair-frame.

The object of this invention is to facilitate the seating of chairs with a plaiting of cane or other material.

The invention consists in a chair-seating needle constructed with a body having four (more or less) rows of alternating spaces and notches with end journals, either or both of which are provided with a screw-collar and with a handle, as will be hereinafter fully described, whereby a uniform diagonal plaiting will be formed, as will be hereinafter fully described.

In making my chair-seating needle I take a rod of iron or other suitable material of convenient size and turn down its end parts, A, to about one-third the diameter of the said rod, leaving the body E of the needle of such a length as to fit in between the front and rear bars of the seat-frame of the chair to be seated, while its end parts or journals, A, rest upon the said bars. Screw-threads are cut upon the outer ends of one or both the parts A, to receive a collar or collars, B, to be screwed up against the front and rear bars, C, of the seat-frame, or against either of them, to prevent the needle from having any longitudinal movement while in use.

For convenience in turning the needle it is provided with a handle, D, on each or either end.

In forming the body E of the needle, beginning with the needle in the position shown in Fig. 2, a rabbet or notch the width of the warp to be used and of a depth equal to about one-third the diameter of the said body is formed 60 in one end. A space of the width of two warp-strands is then left, and a notch or cross-slot the width of two warp-strands is cut in the upper side of the said body, and so on to the other end of the said body, the alternating notches 65 and spaces being of uniform width and depth. The needle is then turned one-quarter of a revolution, and another series of alternate spaces and notches are formed, each equal in width to the width of two warp-strands, and beginning 70 with a space, as in Fig. 3. The needle is then turned through the second quarter of a revolution, and another series of alternate spaces and notches are formed, beginning in this case with a space equal to the width of 75 the warp to be used—that is, of the same width as the rabbet first made—and then continuing with a notch and space alternately, each the width of two warp-strands, as in Fig. 4. The needle is then turned through the third quarter of a revolution, and another series of alternate notches and spaces are formed, each the width of two warp-strands, and beginning with a notch or rabbet, as in Fig. 5. The needle is then turned through the fourth quarter of a 85 revolution, which brings it back to the first position, as in Fig. 2. With this construction a diagonal plaiting will be formed, each strand passing over two strands and under two strands alternately, as hereinafter described.

When making double-bottomed seats, the warp or "first way" is wound around the side bars of the seat-frame by hand, in the ordinary manner. A needle is then passed beneath the warp of the upper part of the seat, 95 and another needle is passed above the warp of the lower part of the seat, the parts A of the needles being held against the front and rear bars of the seat-frame by the said warp, and the needles being held from longitudinal movement by turning the screw-collars B up against the said front and rear bars of the seat-frame. The upper needle being arranged beneath the warp or first way of the

upper part of the seat, Fig. 6, an opening or shed is formed in the strands of this part by some of the warp-strands being elevated above the others by the high portions of the body of the needle, and through this shed a strand of the woof or "second way" is passed, and is then pushed to the other side of the seat-frame. The needle is then turned through one-quarter of a revolution, so as to raise other strands, and another woof-strand is passed through, and so on until the woof extends to or nearly to the needle, which is then removed, and the remaining space is afterward filled out by hand in the ordinary manner. In this way a uniform diagonal plaiting will be formed, each strand of woof passing over two strands of warp and under two strands alternately. The operation of the under needle upon the strands of the under portion of the seat is substantially identical, the strands of the latter being depressed by such needle instead of elevated, as in the case of the upper needle. The elevated or raised parts on the body portion of the needle are arranged in helical order, or like the thread of a screw. Such raised portions support the warp-strands in pairs, which are lifted or raised above the alternating pairs of warp-strands, the latter resting in the hollows between the raised portions. When the needle is revolved, it is thus caused to drop one strand of each raised pair and take up a strand on the

opposite side of the remaining raised strand at each quarter-revolution. A different needle is required for each different width of warp-strands, the raised portions and the notches in each case being the width of two strands, except at each end of the needle, where they run out to the width of one strand, as stated. Should it be desired to change the pattern of the fabric, the depressions and raised portions of the needle may be made of widths corresponding to the width of the alternating numbers of strands. When the chairs and their top rounds are all of one width, the collar or collars B do not require to be adjusted, and they may be integral with the needle.

Having thus described my invention, I claim as new and desire to secure by Letters Patent—

1. A chair-seating needle constructed substantially as herein shown and described, and consisting of the body E, having four (more or less) rows of alternating spaces and notches, journal A, provided with screw-collar B, and handle D, as set forth.

2. A chair-seating needle consisting of the body E, having four (more or less) rows of alternating spaces and notches, the journals A, and handle D, substantially as specified.
